UNITED STATES PATENT OFFICE.

GEORGE W. BUNN, OF FRENCHTOWN, NEW JERSEY.

VEHICLE-SPRING.

SPECIFICATION forming part of Letters Patent No. 311,807, dated February 3, 1885.

Application filed January 17, 1884. (No model.)

To all whom it may concern:

Be it known that I, GEORGE W. BUNN, a citizen of the United States of America, residing at Frenchtown, in the county of Hunterdon, in the State of New Jersey, have invented certain new and useful Improvements in Vehicle-Springs, of which the following is a specification, reference being had to the accompanying drawings, forming a part thereof.

10. This invention relates to springs for side-bar vehicles.

The object of the invention is to provide a spring for this class of vehicles combining a high degree of elasticity with cumulative 15 strength, whereby the vehicle will ride easy under either a light or heavy load.

In the accompanying drawings, Figure 1 is a perspective view of this compound spring. Fig. 2 is an end view thereof, and Fig. 3 is a 20 side view of the same.

The spring side bars, A A, are made somewhat shorter than those in ordinary use, and are preferably provided on their under sides, near their outer ends, with curved lugs *l*. Metallic springs B, attached to the under side of the side bars, and projecting beyond the same in line therewith, connect with half-elliptic springs C C', which rest upon the hind axle and bolster, respectively. These half-elliptic 25 springs may be of sufficient strength to support a weight of six hundred pounds. The vehicle-body is supported on cross-springs D D', which are clipped to the side bars and supported thereby. These cross-springs are each 30 preferably composed of a flat wooden bar or follower, D', and downwardly-inclined steel springs D'', the inner ends of which are attached to the follower near its center, said follower being provided with two curved lugs, *f*, on 35 the under side, between its center and its ends,

which lugs come in contact with the steel springs D'' and give support to the latter as the weight is increased. The spring thus constructed embraces three sets of metallic springs, which co-operate with each other in 45 such a manner as to cause the vehicle to ride easy, whether it be lightly or heavily loaded. When these sets of springs are of the form herein shown, the vehicle will maintain a steady carriage whether on level or inclined 50 ground.

I am aware that each of the several parts of this compound spring has been used before in different combinations.

What I claim as my invention is—

1. The combination of cross-springs adapted to receive the vehicle-body, spring side bars supporting said cross-springs, longitudinal steel springs at the ends of said side bars, and transverse half-elliptic springs connecting 60 the longitudinal springs, substantially as described.

2. The combination of cross-springs adapted to receive the vehicle-body, each composed of steel springs, and a follower provided with 65 curved lugs on its under side near its ends; spring side bars supporting said cross springs, and provided with curved lugs on their under sides near their ends, transverse end springs adapted for attachment to the hind axle and 70 bolster, respectively, and downwardly-inclined longitudinal steel springs connecting said side bars with said transverse end springs, said longitudinal steel springs passing under the curved lugs of the side bars, substantially 75 as described.

GEORGE W. BUNN.
